RADIO TUBE

Abraham Binneweg, Jr., Oakland, Calif.

Application July 30, 1942, Serial No. 452,855

9 Claims. (Cl. 250—27.5)

My invention relates to improvements in vacuum tubes for radio and the object of my improvement is to provide an electronic tube for general radio purposes of suitable plastic material. Further objects are to provide a tube wall cooled by circulating water, air, or other fluid thereagainst; to provide simple quick means for assembling, taking apart, and element replacement; to provide means for sealing the tube; and also to provide a method of assembly. Further objects will appear from the following drawing and description.

In the drawing, Figure I is a vertical section of the tube, and Figure II a top view with part of the cap removed.

The tube consists of a base 1 of porcelain or of polystyrene or other plastic material, provided with holes 2 for attachment to a radio chassis or base, a shell 3, fastened to the base 1 by bolts 4 and 5, and a cap 6 attached or sealed to the top of the shell or case 3 by bolts 7. The shell or case 3 is provided with a hollow space 8 within the shell wall for the circulation of cooling liquids or gases which may enter at the orifice through screw 9, circulate against the walls passing out through the hollow screw 10. The outer wall could also be grooved if no cooling chamber is used. The top, shell, and base need not be of the same plastic material.

Within the shell is a thin, metallic, hollow, cylindrical or square electronic plate 11 of ordinary construction, preferably open at both ends, and within this plate is a cylindrical or square grid consisting of a plurality of vertical wires 12 encircled by a wire helix 13, or by loops. Within this grid is a hollow cathode 14, and within the cathode a heater filament 15.

Wires lead from the various elements for electrical connection: grid lead 17, plate lead 18, cathode lead 16, and filament leads 19. These leads, one or more to each element, pass through plastic or metallic caps 20, and are cemented in place.

Through the shell cap 6, pass two or more knurled or threaded tubes 21, one use being for exhausting the shell. These are pinched together at the end and may be soldered or welded. These tubes could optionally be formed as a part of the tube top 6. The second tube is provided to serve as a connection to an element, or for reexhausting the element chamber if the tube is opened to replace a part.

Grooves 22 are cast or cut in the inner wall of the shell. One purpose is to provide space and prevent radio-frequency losses between plate 11

and the shell wall. Such grooves could be omitted for small tubes. Soft plastic gaskets 23 may be placed between shell 3 and base 1, and also between the shell and cap 6 to afford an air tight seal. If no water chamber is needed, parts 1 and 3 could be formed in one piece.

Circular grooves 24 are provided in the bottom of the shell 3 for retaining the ends of plate, grid, and cathode, and similar grooves 25 are in the cap 6 above. Extra grooves could be provided in between, of the same or of different depths for elements of different sizes. A threaded insert 26 serves to hold the bolt 5. The bottom of the shell under insert 26 could also be gasketed. If the parts are carefully fitted, no gaskets may be necessary.

By removing nuts 27 the cap 6 may be removed for the replacement of filaments or other parts. The parts of the shell, once proper elements are found, can be permanently cemented together.

The complete electronic tube is assembled by placing the plastic disk 1 flat and setting into the proper grooves 24, the desired cathode 14, the desired grid 12, and the desired plate 11. These elements fit snugly in the selected respective grooves. The leads are then drawn through holes in the shell wall 3 and element wall, 11, and the cover 6 and the nuts 27 are tightened. The little caps 20 if used are then cemented at the sealed orifices. One of the tubes 21 is plugged, and the open one is used to exhaust the inner chamber after which it is pinched off and soldered or welded shut. If an exhaust tube is left long, it can be cut off and used again.

If exhaust tube 21 is metallic, it may also be used as a grid lead making direct grid contact or by use of wire 28, connecting tube 21 and grid 12. The second exhaust tube could likewise be used as an element lead if desired. Cement 30 may fill the connection caps 20. The holes through which the stiff or flexible leads pass can themselves be cemented or sealed, no lead caps being necessary. A lead could pass up through an exhaust tube. To hasten exhaustion, the exhaust could be through more than one tube.

The threaded cylindrical insert 26 holds the machine screw 5 which in turn fastens together the shell 3 and the base 1.

Having thus described the invention, what I claim is new is:

1. A vacuum tube comprising a cup-shaped dielectric receptacle, a removable dielectric cap for said receptacle, circular grooves in the bottom of said receptacle, circular grooves in said cap, cy.

lindrical cathode, grid and plate elements held in place by said grooves, and means for removably affixing said cap to said receptacle.

2. A vacuum tube comprising a cup-shaped nonconducting receptacle, a removable cap for said receptacle, conductive exhaust tubes perforating said cap, concentrically disposed cathode, grid, and plate elements within said receptacle, and electric conductors connecting said elements and said exhaust tubes.

3. The combination of a vacuum tube comprising a porcelain cup, a waterway in the walls of said cup, a removable cap for said cup, a gasket between said cup and said cap, removable cathode, grid, and plate elements within said cup, a plurality of exhaust tubes penetrating said cap, electric conductors connecting said tubes and said elements, and a porcelain base for the tube removably attached thereto.

4. A vacuum tube having a cylindrical chamber, an axial cathode within said chamber, a conductor from said cathode passing through the top of said chamber, a grid surrounding said cathode, a plate surrounding said grid, a lateral aperture in said plate, a conductor attached to said grid, passing through said aperture and through the wall of said chamber, and a conductor attached to said plate and passing through the wall of said chamber.

5. A vacuum tube having an inner dielectric cup-shaped chamber, insulated electrodes within said chamber, a removable dielectric cap for said chamber, an outer cylindrical chamber surrounding said inner chamber and having walls integral at the top with the walls of said inner chamber, an annular opening equal in diameter with said outer chamber for said outer chamber at the bottom of the tube, and a removable closure for said outer chamber.

6. A radio tube comprising a cylindrical block.

of dielectric material, a central cylindrical chamber extending downward nearly to the bottom of said block, an outer annular cooling chamber extending upwardly nearly to the top of said block

5 and having an annular opening of equal diameter therewith, a dielectric closure at the top for said inner chamber, and another closure at the bottom for said outer chamber, and concentrically arranged electrodes within said central chamber.

10 7. A vacuum tube comprising a cup-shaped dielectric receptacle, a removable dielectric cap for said receptacle, corrugations on the inner wall of said receptacle, a cylindrical anode adjacent said corrugations and supported thereby, a cylindrical grid enclosed by said anode and concentric therewith, a cylindrical cathode at the center of said receptacle, and concentric circular grooves in the bottom of said receptacle and also in the under surface of said cap for holding in spaced relation said anode, grid, and cathode.

15 8. A radio tube comprising a cylindrical plastic receptacle integrally closed at the bottom, a plastic cap for said receptacle, metal exhaust tubes in said cap to be used also as leads, concentric circular grooves in the bottom of said receptacle, similar grooves in the under surface of said cap, electrodes supported in spaced relation by said grooves, and conductors, each connecting one of said electrodes with one of said exhaust tubes.

20 9. A radio tube having a cylindrical receptacle, an axial electrode within said receptacle, concentric cylindrical electrodes surrounding said axial electrode, holes in said surrounding electrodes, lateral holes in said receptacle, and wire conductors attached to said electrodes, thence passing through the holes in said electrodes and said receptacle to the exterior.
